UNITED STATES PATENT OFFICE.

JOHN C. ROBBINS, OF WALTHAM, MASSACHUSETTS.

DESIGN FOR A BICYCLE-FRAME.

SPECIFICATION forming part of Design No. 30,733, dated May 9, 1899.

Application filed March 17, 1898. Serial No. 709,555. Term of patent 7 years.

To all whom it may concern:

Be it known that I, JOHN C. ROBBINS, of Waltham, in the county of Middlesex and State of Massachusetts, have invented and 5 produced a new and original Design for Bicycle-Frames, of which the following is a specification, reference being had to the accompanying drawings, forming part thereof.

In the drawings, Figure 1 represents a side elevation of a bicycle-frame, illustrating my new design. Fig. 2 represents a sectional view of the same, taken on line 22, Fig. 1.

The leading feature of my new design for bicycle-frames consists in the design as herein 5 shown and described.

As shown in the drawings, the outline of

the central member 5, at the lower portion or surface 6 thereof, is broken by the depending straight line 7, extending to the cross-line 8, which cross-line again meets the surface 6 between the lines 7 and 8, and merging into the general surface 6 is the cylindrical portion 9, the lower end of which is indicated by the line 8.

What I claim is—

The design for a bicycle-frame as herein shown and described.

JOHN C. ROBBINS.
